No. 853,793.

PATENTED MAY 14, 1907.

J. E. HULSE.

MOP.

APPLICATION FILED AUG. 22, 1906.

UNITED STATES PATENT OFFICE.

JEROME E. HULSE, OF ALBANY, NEW YORK.

MOP.

No. 853,793.

Specification of Letters Patent.

Patented May 14, 1907.

Application filed August 22, 1906. Serial No. 331,648.

To all whom it may concern:

Be it known that I, JEROME E. HULSE, a citizen of the United States, residing at Albany, in the county of Albany and State of New York, have invented certain new and useful Improvements in Mops; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in mop heads, and the object of the invention is to produce a simple and efficient device of this nature comprising, in connection with the spring-pressed wringer rollers which form a part of the head and between which the mop may be wrung, the provision of a fixed and a pivotal locking jaw, whereby the ends of the mop may be securely held, and so arranged that the same may be readily removed when desired for any purpose.

The invention comprises various other details of construction and combinations and arrangements of parts which will be herein-after fully described and then specifically defined in the appended claims.

I illustrate my invention in the accompanying drawings, in which:—

Figure 1 is a side elevation of my improved mop, showing the handle for operating the wringers, locked to prevent the rollers from rotating. Fig. 2 is a perspective view of the end of the mop, showing the jaws open and the ends of the mop detached therefrom. Fig. 3 is an edge view, and Fig. 4 is a cross sectional view through the jaws, showing one jaw in dotted lines, open.

Reference now being had to the details of the drawings by letter, A designates the frame of the head which has two parallel arms which are provided with elongated slots A', and a shank portion B adapted to receive a handle C.

D and D' designate wringer rollers having spindle ends which are mounted in said elongated slots. The spindles of the roller D' are held against the ends of said slots by means of the roller D against which the angled ends of a bar E bear, which angled ends are positioned within said slots. The bar E has shoulders E' which bear against the inner

faces of the parallel portions of the frame in which are formed said slots. F designates a spring which is bent at its longitudinal center to form a loop F', and thence bent into coils F'' each of which bears against the bottom of a recess H formed in the outer face of said bar, while the ends of the spring extend into the shank portion of said frame, where they are securely anchored by the end of the handle of the mop which is inserted in said shank. One of said rollers D is provided with a crank arm d, to the end of which is pivotally connected a handle N having an eye N' at the free end thereof which is designed to engage a resilient hook O fixed to the handle, as clearly shown in the side elevation of the drawings, said eye being adapted to engage the hook, the resiliency of which holds the same rigidly when it is desired to hold the rollers from rotation. When the handle is desired for use in rotating the wringer rollers, the same may be loosened from the hook by pulling the same away from the head of the mop, and swung around into the position shown in dotted lines in Fig. 1 of the drawings. At one end of the frame is a fixed jaw Q having teeth Q' projecting from the inner face thereof and adapted to engage apertures formed in the ends of the mop.

S designates a pivotal jaw having a flange S' projecting therefrom at right angles adjacent to its edge, and each angled end I' of the pivotal jaw is provided with a recess I adapted to receive the angled ends J of the pivotal spring-dogs J' which are mounted upon the arms of said frame adjacent to the outer ends thereof. The extreme ends of the arms carrying said dogs are recessed, as at T, for the reception of the angled ends of the dogs, the recesses in the ends of the pivotal jaw and said arms being adapted to register with each other when the jaws are closed, in which positions they are locked by the angled ends of the dogs engaging said registering recesses.

In applying the mop to the frame, it is passed between the rollers and the ends of the mop, which are provided with apertures, are caught over the teeth which project at right angles upon the fixed jaw of the frame, and the pivotal jaw swung closed and locked, in which position the flange thereof will bear against the ends of said teeth and hold the ends of the mop securely. When it is desired to wring the mop, the handle is de-

tached from its resilient retaining hook and thrown out to the position shown in dotted lines in Fig. 1, in which it may be utilized for causing the mop to be wrung by its being turned back and forth between the wringer rollers. The spring bearing against the bar will securely hold the wringer rollers so that the mop will be clamped thereby.

From the foregoing, it will be noted that by the provision of a mop head made in accordance with my invention, a simple and efficient device is afforded whereby the mop may be securely held by the fixed and pivotal jaws, while the same may be readily wrung by simply turning the handle back and forth. When the handle is not utilized for causing the wringer rollers to rotate, it may be swung back and made to engage the hook, thereby securely locking the rollers from rotation.

20 What I claim is:

1. A mop head comprising a frame having arms provided with slots, wringer rollers having spindles mounted in said slots, a bar having angled ends mounted in said slots and bearing against the spindles of one of said rollers, a spring bearing yieldingly against said bar, a fixed jaw at one end of said frame and provided with teeth, a pivotal jaw mounted upon said arms, and spring-dogs 25 mounted upon said arms and having angled ends which are designed to engage registering recesses formed in the two jaws, whereby the latter may be held locked together, as set forth.
- 35 2. A mop head comprising a frame having arms provided with slots, wringer rollers having spindles mounted in said slots, a bar having angled ends mounted in said slots and bearing against the spindles of one of said 40 rollers, a spring bearing yieldingly against

said bar, a fixed jaw at one end of said frame and provided with teeth at right angles therefrom, said arms having recesses in the ends thereof, a pivotal jaw having angled ends which are pivotally connected to said arms, the ends of said pivotal jaw having recesses adapted, as the pivotal jaw is swung against said teeth, to register with the recesses in the ends of said arms, and spring-dogs mounted upon the arms and having angled ends designed to engage said registering recesses, as set forth.

3. A mop head comprising a frame having arms provided with slots, wringer rollers having spindles mounted in said slots, a bar 55 having angled ends mounted in said slots and bearing against the spindles of one of said rollers, a spring bearing yieldingly against said bar, a fixed jaw at one end of said frame and provided with teeth at right 60 angles therefrom, said arms having recesses in the ends thereof, a pivotal jaw having angled ends which are pivotally connected to said arms, the ends of said pivotal jaw having recesses adapted, as the pivotal jaw is 65 swung against said teeth, to register with the recesses in the ends of said arms, and spring-dogs mounted upon the arms and having angled ends designed to engage said registering recesses, the outer swinging edge of said 70 pivotal jaw having an angled flange adapted to extend over the ends of said teeth when the jaws are held together, as set forth.

In testimony whereof I hereunto affix my signature in the presence of two witnesses. 75

JEROME E. HULSE.
